UNITED STATES PATENT OFFICE.

CHARLES L. DEPOLLIER, OF NEW YORK, N. Y.

WATCHCASE, &c.

1,169,777.

Specification of Letters Patent.

Patented Feb. 1, 1916.

Application filed February 1, 1915. Serial No. 5,414.

To all whom it may concern:

Be it known that I, CHARLES L. DEPOLLIER, a citizen of the United States, residing in the borough of Brooklyn, of the city of New York, in the county of Kings, in the State of New York, have invented certain new and useful Improvements in Watchcases, &c., of which the following is a specification, reference being had to the accompanying drawing, forming a part hereof.

This invention relates particularly to what are commonly known as convertible watches, that is, watches which can be used either as wrist watches or as chatelaine or sautoire watches. Such watches, in order to be used as wrist watches, must be provided at opposite points with two means of attachment to the bracelet. The bow of the watch usually serves as one of such means of attachment and at the opposite point the watch-case is usually provided with a projecting eye or loop of some sort to which one end of the bracelet may be secured. It has been proposed heretofore to provide, as such second means of attachment, something which shall not be readily visible when the watch is in use as a chatelaine or sautoire watch, in order that it may not appear that the wearer is then using a convertible watch, that is, a watch which, for economy, may be used either for one purpose or another purpose.

It is the object of this invention to provide a means for connecting a watch to a bracelet or the like which shall not be readily seen, so that when the watch is used as a chatelaine or sautoire watch, there shall be nothing about it readily visible to suggest that the watch is also used sometimes as a wrist watch. In accordance with the invention the watch-case center is provided at a point opposite the bow, or at each of two points, if desired, with a recess and a bar spanning the recess but flush with the periphery of the center, so that a hook or snap ring or the like, at the end of a chain or bracelet, may be engaged therewith, whereby the watch-case, unless seen in edge view and from one side only, shall have the appearance of an ordinary watch-case with no projecting part to suggest adaptation to another use.

The invention will be more fully explained hereinafter with reference to the accompanying drawing in which it is illustrated and in which—

Figure 1 is a view in perspective of a bracelet and a watch equipped with the improved device. Fig. 2 is a view on a larger scale, partly in elevation and partly in section, of a watch-case which embodies the invention, the terminal link of a bracelet being also shown in operative engagement therewith. Fig. 3 is an edge view of the watch-case shown in Fig. 2. Fig. 4 is a view similar to Fig. 2, but showing the bar which spans the recess arranged longitudinally instead of transversely and as engaged by a snap ring. Fig. 5 is an edge view of the watch-case shown in Fig. 4, partly in section on the plane indicated by the line 5—5 of Fig. 4. Fig. 6 is an edge view of the watch-case shown in Fig. 4 as seen from the right hand in said figure.

In Fig. 1 of the drawing is shown a wrist or bracelet watch *a* having an ordinary bow *b* to which is attached one end of a bracelet *c*, the other end being attached to the watch at a point, as *d*, diametrically opposite the bow *b*, as hereinafter described.

In each of the embodiments of the invention illustrated in the drawing the center *e* of the watch-case, having on one side the back *e'* and on the other side the bezel *e''*, has formed therein at a convenient point, preferably opposite the bow *b*, or at each of two diametrically opposite points, a recess *e³*, which is preferably dished as shown so as to facilitate the introduction of a hook or ring.

In each of the embodiments illustrated there is provided a bridge or bar *f* or *f'*, which spans the recess *e³*. In the embodiment shown in Figs. 2 and 3, this bar or bridge *f* is transverse with respect to the watch-case center, while in the embodiment illustrated in Figs. 4, 5 and 6 the bridge or bar *f'* is longitudinally disposed. In either case the bridge or bar is substantially flush with the periphery of the center and does not project beyond it so as to be readily seen.

In the embodiment illustrated in Fig. 2 the terminal link of the bracelet *c* is shown as composed of two members *c'* and *c²*, adapted for relative longitudinal movement, the member *c²* having a hook *c³* which is adapted to be engaged with the bar *f*. In the embodiment illustrated in Figs. 4 and 5 the terminal link *c⁴* is shown as connected, through a swiveled eye *c⁵*, with an ordinary snap ring *c⁶* for engagement with the bar *f'*.

It will be observed that this form of securing device is inexpensive and is well adapted for watches of certain kinds.

I claim as my invention:—

- 5 1. A watch-case having its center formed with a recess and a bar spanning such recess substantially within the periphery of the center and adapted for engagement by a hook or ring.
- 10 2. A watch-case having its center formed with a dished recess and a bar spanning the recess flush with the periphery of the center and adapted for engagement by a hook or ring.
- 15 3. A watch case having a bow adapted for connection with a hook or ring and having its center formed with a recess opposite the

bow and a bar spanning such recess substantially within the periphery of the center and adapted for engagement by a hook or ring.

4. A watch case having a bow adapted for connection with a hook or ring and having its center formed with a dished recess opposite the bow and a bar spanning the recess flush with the periphery of the center and adapted for engagement by a hook or ring.

This specification signed and witnessed this 29th day of January A. D., 1915.

CHARLES L. DEPOLLIER.

Signed in the presence of—

FRANCIS J. MURPHY,
WORTHINGTON CAMPBELL.
